UNITED STATES PATENT OFFICE.

WILLIAM HUGH WOODCOCK, OF LONDON, ENGLAND.

ROLLER-BEARING.

SPECIFICATION forming part of Letters Patent No. 557,042, dated March 24, 1896.

Application filed November 8, 1895. Serial No. 568,370. (No model.)

To all whom it may concern:

Be it known that I, WILLIAM HUGH WOODCOCK, a subject of the Queen of Great Britain and Ireland, residing at 25 Auckland Hill, 5 West Norwood, London, in the county of Surrey, England, have invented new and useful Improvements in Roller-Bearings, of which the following is a specification.

This invention relates to roller-bearings; 10 and it consists in the novel construction and combination of the parts hereinafter fully described and claimed.

Figures 1, 2, 3, 4, 5, and 6 represent an application of my improvements to a railway 15 axle-box, the left half of Fig. 1 being an end elevation, and the right a cross-section on line X Y, Fig. 2, Fig. 2 being a part sectional elevation, Fig. 3 being a half-plan on top of box, Fig. 4 being a plan of cradle formed 20 of one piece of metal, with the rollers and their bearing-pieces in position ready for insertion into the casing, Fig. 5 being an end elevation of roller and bearing-piece, and Fig. 25 6 a cross-section of same on line V W, Fig. 5.

Referring to the drawings, *a* is the journal at the end of the axle of a railway-vehicle.

b is the sleeve of hardened steel, wrought-iron case-hardened, chilled cast-iron, or other suitable material, which is shrunk on or otherwise fastened to the axle-journal *a*.

c is the casing or axle-box, preferably made of cast-steel.

d is the front cover of axle-box.

e is a disk of gun-metal, phosphor-bronze,

or other suitable material, to take the end 35 pressure of the axle.

ff are the rollers placed between the journal-sleeve and the casing.

g is the metal cradle, and *hh* are the bearing-pieces for the roller ends *f*, Fig. 2, these 40 bearing-pieces being fitted into the ends *g*' and between the arms *g*² of the cradle *g*. The roller end bearing-pieces *hh* are provided with lips or projections *h*' which fit over the ends *g*' of the cradle *g*, and by this means the 45 cradle *g* is maintained in its concentric position with the journal, the lateral movement of the cradle *g* with reference to the rollers *f* being prevented by the body of the bearing-pieces *hh*. 50

ii are projections on the sleeve to prevent the rollers *f* and cradle *g* from moving laterally.

What I claim is—

The combination with a circular casing, a 55 shaft journaled concentric with the said casing, and projections *i* connected with the said shaft; of a cradle provided with arms extending between its ends and bearing-pieces *h* carried by its ends; and rollers interposed 60 between the said casing and shaft, engaging with the said projections on the shaft, and journaled in the said bearing-pieces of the cradle, substantially as set forth.

WILLIAM HUGH WOODCOCK.
